UNITED STATES PATENT OFFICE

2,150,721

CHAIR

Anna A. Mullooly, Greensburg, Pa.

Original application December 14, 1935, Serial No. 54,485. Divided and this application May 5, 1936, Serial No. 78,052. Renewed October 22, 1938

2 Claims. (Cl. 155—127)

My invention relates generally to a chair of the type used in beauty parlors, and particularly to a chair of this general character which involves adjustable shelf structure permitting supporting before the customer various articles of utility and convenience, while the customer is having a facial or a hair treatment, and an important object of my invention is to provide convenient and attractive arrangement of this character which is highly practical.

Another important object of my invention is to provide in a chair of the character indicated, a shelf structure which includes two or more shelves which are so connected to the chair that either the customer or the operator may bring into operative position or restore to inoperative position either of the shelves, the same shelves being completely out of the way when in the inoperative position.

Other important objects of my invention will be apparent from a reading of the following description in connection with the drawings, wherein for purposes of illustration I have shown a preferred embodiment of my invention.

In the drawings:—

Figure 1 is a general side elevational view of the chair.

Figure 2 is a front elevational view of Figure 1.

Figure 3 is a bottom plan view of one of the shelves showing the dual tracks.

Figure 4 is a transverse vertical sectional view taken through an arm portion of the chair and showing the manner of mounting of the track engaging brackets thereon.

Figure 5 is a transverse vertical sectional view taken through Figure 3.

Figure 6 is an elevational view of one of the track engaging brackets.

Figure 7 is a transverse vertical sectional view taken through the ash receiver.

Figure 8 is a transverse vertical sectional view taken through Figure 2 approximately on the line 8—8.

The subject matter of the within application is a division of my co-pending application Serial No. 54,485, filed December 14, 1935, and entitled "Beauty parlor chair."

Referring in detail to the drawings, the numeral 5 generally designates the chair which is in general form conventional and includes the seat 6, the back 7, the foot rest 8, and the padded leg rest 9, these parts being supported by the leg arrangements 10 immediately supporting the chair frame 11 on which the back 7 is mounted, and the arm rests 12.

The left hand arm 12 of the chair has fastened thereto the hinge plates 41 of the character shown in Figure 6 which include the fastening plate 42, the lateral projection 43, and the upstanding T-shaped member 44 which is arranged to engage in one of the tracks 45 on the bottom of the shelf 46, the said shelf being provided with two of the said tracks, and the hinge members 41 being respectively engaged in corresponding tracks and fastened to the laterally outward side 10 of the chair arm. A second pair of similar hinge members 41' are similarly fastened to the laterally outward side of the right hand chair arm 12'.

By means of the hinge members 41 which have their T-heads inserted slidably in the tracks 45, the shelf 46 is slidably and pivotally attached to the chair arm and has beginning at the left hand end thereof the ash tray 47, the cigarette holder 48, the book holder 49, and the fountain pen holder 50, mounted thereon in the order 20 named from left to right.

Similarly connected by the hinge members 41' to the arm 12' is the shelf 51 which contains in order from left to right the ash tray 47', the powder compact 52, the mirror 53, and a drinking vessel retainer 54.

The form of the track engaging hinge members 41 and 41' is clearly shown in Figure 6. In Figure 4 the plate 42 is shown as attached to the arm 12 adjacent the upper edge thereof, and the upper end of the plate 42 is provided with a pin barrel 55 with which a hinge pin 56 is engaged, which hinge pin traverses also the portion 57 of the T-shaped member 44, whereby the part 44 is pivoted relative to the plate 42.

The ash tray 47, similar in all respects to the ash tray 47', comprises a base 58 which is attached to the top of the shelf and has rising therefrom the inverted L-shaped arms 59 and 60 which have their foot portions inwardly directed 40 to engage pivotally in sockets 61 and 62 on the upper part of the generally cylindrical receiver 63 which has the rounded bottom 64 filled with weighting material 65. The receiver 63 has its upper end closed by a removable concave closure 45 66 which has the ash passing opening 67 therein. Whenever either of the shelves is tilted the receptacle 63 rights itself so as to be always in an upright position ready to receive ashes.

The cigarette holder 48 has the construction shown clearly in Figure 8, and consists of a shallow pan 68 fixed by screws or the like 69 to the top of the shelf 46. A dividing partition 70 is mounted across the pan 68 and has hinged thereto as indicated by the numeral 71 the retaining 55 66

fingers 72. The partition also mounts the closing springs 73 which cooperate with the fingers to hold the cigarettes 74 in place in the pan.

With the foregoing arrangements provided, it is obvious that the customer may during hair beautifying operations, conveniently smoke, read, write, put on make-up, or combine any or all of these undertakings while in a sitting up or in a reclining position. It is also obvious that the customer may herself operate the shelves selectively into position, it being obvious that a selection may be preferable between the two shelves 46 and 51, because of the difference in the nature of the articles on the respective shelves. A selected shelf may be brought into place as is the shelf 46 shown in Figure 2 simply by swinging and sliding the shelf on the corresponding hinge members, supposing that the remaining shelf was not already in operative position. In the latter instance, the shelf already in position is swung outwardly and downwardly and permitted to slide to the dependent position illustrated in Figure 2, before the other shelf is brought up and across into position.

Although I have shown and described herein a preferred embodiment of my invention, it is to be definitely understood that I do not desire to limit the application of the invention thereto, and any change or changes may be made in the materials, and in the structure and arrangement

of the parts, within the spirit of the invention and the scope of the subjoined claims.

What is claimed is:—

1. In a chair of the character described having two arm rests, a hinge member on one of said arm rests, said hinge member comprising a plate fastened to the arm rest, and a T-shaped track engaging member pivoted on said plate, a shelf having a track on its underside, said T-shaped member having its arms rounded and pivotally and slidably engaged with said track, whereby said shelf may be brought into a position overlying and engaging the two arm rests or disposed so as to depend laterally outwardly of the corresponding one of said arm rests. 15

2. In a chair of the character described having two arm rests, a hinge member on each arm rest, each hinge member comprising a plate fastened to the side of the corresponding arm rest, and a T-shaped track engaging member pivoted 20 on said plate, a shelf having a track on its underside, said T-shaped member having its arms rounded and pivotally and slidably engaged with said track, whereby said shelf may be brought into a position overlying and engaging the two 25 arm rests or disposed so as to depend laterally outwardly of the corresponding one of said arm rests.

ANNA A. MULLOLLY. 30
